[57] CLAIM

An ornamental design for a dental floss dispenser, as shown and described.

DESCRIPTION

FIG. 1 is a perspective view of a dental floss dispenser on a reduced scale, the broken line drawing of dental floss is for illustrative purposes only and forms no part of the claimed design;

FIG. 2 is a front elevational view;

FIG. 3 is a rear elevational view;

FIG. 4 is a first side elevational view;

FIG. 5 is a second side elevational view;

FIG. 6 is a top plan view of the embodiment; and,

FIG. 7 is a bottom plan view.

DATED : February 20, 1996

INVENTOR(S) : Dunn

It is certified that error appears in the above-identified patent and that said Letters Patent is hereby corrected as shown below:

The title page, showing an illustrative figure, should be deleted and substituted therefor the attached title page.

In the Drawings:

Delete drawing sheets 1-3, and substitute therefor the Drawing sheets, consisting of Figures 1-7, as shown on the attached pages.

Signed and Sealed this
Sixth Day of August, 1996
